UNITED STATES PATENT OFFICE.

WILLIAM C. CODMAN, OF PROVIDENCE, RHODE ISLAND.

DESIGN FOR A HANDLE FOR SPOONS, &c.

SPECIFICATION forming part of Design No. 27,850, dated November 16, 1897.

Application filed October 6, 1897. Serial No. 654,295. Term of patent 7 years.

To all whom it may concern:

Be it known that I, WILLIAM C. CODMAN, a subject of the Queen of Great Britain, residing at Providence, in the county of Providence and State of Rhode Island, have invented and produced a new and original Design for the Handles of Spoons, Forks, and Similar Articles, of which the following is a specification, reference being had to the accompanying drawings, forming part thereof.

Figure 1 is a view of the obverse side of the handle, showing the same attached to the bowl of a spoon. The tines of a fork are indicated in broken lines. Fig. 2 is a view of the reverse side of the handle, showing the same attached to the bowl of a spoon.

The leading feature of my design consists in the marginal ornamentation of the handle formed of alternately inward and outward curved scrolls, giving to the handle what is known in the art as the "rococo" or "Louis-Quatorze" appearance.

In the drawings, A indicates the handle, and B the bowl, of the spoon. From the junction of the bowl with the handle extend the

scrolls 3, from which springs the outwardly curved scrolls 4. The inward and then the outward curving scrolls 5 extend from the scrolls 4 to the scrolls 6, and from this extend the double scrolls 7 8. The scrolls 9 30 complete the stem or narrow portion of the handle, and the scrolls 10 curve considerably outward to form the margin of the panel of the blade of the handle. These are surmounted by the inwardly-curved scrolls 11, from 35 which extend the outwardly-curved foliated scrolls 12, the upper parts of which abut against the central shell ornament 13, which forms the upper end of the handle.

Having thus described my newly-produced 40 design, what I claim as new, and desire to secure by Letters Patent, is—

The design for the handles of spoons, forks and similar articles herein shown and described.

WILLIAM C. CODMAN.
